UNITED STATES PATENT OFFICE.

AUGUSTUS KLOCKER, OF THOMASTON, CONNECTICUT, ASSIGNOR TO THOMASTON KNIFE COMPANY, OF THOMASTON, CONNECTICUT.

POCKET-KNIFE.

1,134,539.

Specification of Letters Patent.

Patented Apr. 6, 1915.

Application filed July 7, 1914. Serial No. 849,409.

To all whom it may concern:

Be it known that I, AUGUSTUS KLOCKER, residing at Reynolds Bridge, Thomaston, county of Litchfield, and State of Connecticut, a citizen of the United States, have invented certain new and useful Improvements in Pocket-Knives; and I do hereby declare the following to be a full, clear, and exact description of the invention, such as will enable others skilled in the art to which it pertains to make and use the same.

My invention relates to improvements in pocket knives and more particularly to a pocket knife having a blade in the form of a cutting, punching and reaming tool for use by saddlers, shoe and belt makers and other leather workers, mechanics, farmers and others.

It has for its object to provide a pocket knife having a single blade which embodies several different tools.

It further has for its object to provide a pocket knife having a blade for the purposes set forth which is inexpensive and durable in construction and very handy and effective in use.

Referring to the drawings:—Figure 1 is a front view of the pocket knife with the blade extended. Fig. 2 a cross-section on line $x-x$ of Fig. 1. Fig. 3 a cross-section on the line $y-y$ of Fig. 1. Fig. 4 a longitudinal section on line $z-z$ of Fig. 1. Fig. 5 a rear view of the blade.

In the drawings in which like reference characters denote like parts throughout the several views, 1 represents the handle of the knife, 2 the blade pivoted at 3 therein and which comprises a tang 4, a straight cutting edge 5, next to or adjoining the tang, a triangular concave portion 6, a convex portion 7, a tapering or inclined cutting edge 8, a rounded, non-cutting, edge 9 and a sharp rounded end 10.

The cutting edge 5 is to be used in a similar manner to the usual knife blade and when the point 10 is made to penetrate the

leather or other material and the blade turned in the direction of the cutting edge 8 it will cut a hole, the size being regulated by the distance that the blade is inserted 50 therein, and when the blade is turned in the opposite direction the rounded edge 9 will ream or smooth the hole previously formed by the cutting edge 8.

I do not desire to be understood as limiting myself to the specific details of construction and arrangement herein described and illustrated, as it is manifest that variations and modifications may be made in the features of construction and arrangement 60 by the adaptation of the device to various conditions of use without departing from the spirit and scope of my invention and improvements. I therefore, reserve the right to all such variations and modifications as properly fall within the scope of my invention and the terms of the following claims.

What I claim is:—

1. In a pocket knife, a blade having a 70 straight cutting edge, a concave portion with a tapering cutting edge and a tapering rounded edge, substantially as described.

2. In a pocket knife, a blade having a 75 tang, a straight cutting edge adjoining said tang and a triangular shaped concave portion adjoining the straight cutting edge, provided with cutting and rounded edges, substantially as described.

3. In a pocket knife, a blade having a 80 straight cutting edge, a tapering cutting edge, a tapering rounded edge and a concave portion extending from the tapering cutting edge to the tapered rounded edge, substantially as described.

In testimony whereof I affix my signature in the presence of two witnesses.

AUGUSTUS KLOCKER.
